UNITED STATES PATENT OFFICE

163,062

POCKETBOOK OR SIMILAR ARTICLE

Simon Morrison, New York, N. Y.

Application October 11, 1950, Serial No. 12,521

Term of patent 7 years

(Cl. D87—3)

To all whom it may concern:

Be it known that I, Simon Morrison, a citizen of the United States, and a resident of New York city, in the county of New York and State of New York, have invented a new, original, and ornamental Design for Pocketbook or Similar Article, of which the following is a specification, reference being had to the accompanying drawing, forming part hereof.

Fig. 1 is a front elevation of a pocketbook, showing my new design, a portion of the handle being disclosed in broken lines;

Fig. 2 is a side elevation thereof, portions of the handle being omitted for convenience of illustration; and

Fig. 3 is a sectional view of the front shell of the pocketbook, taken on the line 3—3 of Fig. 1.

The pocketbook is substantially the same in appearance on both sides.

I claim:

The ornamental design for a pocketbook or similar article, substantially as shown and described.

SIMON MORRISON.
